UNITED STATES PATENT OFFICE.

IVAR BENSON, OF SEATTLE, WASHINGTON.

DESIGN FOR A TONE-CHAMBER FOR PHONOGRAHS.

55,361.

Specification for Design.

Patented June 1, 1920.

Application filed March 25, 1920. Serial No. 368,761. Term of patent 7 years.

To all whom it may concern:

Be it known that I, IVAR BENSON, a citizen of the United States, residing in the city of Seattle, county of King, and State of Washington, have invented a new, original, and ornamental Design for a Tone-Chamber for Phonographs, of which the following is a specification, reference being had to the accompanying drawings, forming a part thereof.

In the drawings Figure 1 is a top plan view of my tone chamber;

Fig. 2 is a view in side elevation of the same;

Fig. 3 is a view in rear elevation; and

Fig. 4 is a view in front elevation.

I claim:

The ornamental design for a tone chamber for phonographs as shown.

IVAR BENSON.
